UNITED STATES PATENT OFFICE.

GEORGE C. FAVRE, OF SOUTHBIDGE, MASSACHUSETTS, ASSIGNOR TO AMERICAN OPTICAL COMPANY, OF SOUTHBIDGE, MASSACHUSETTS, A VOLUNTARY ASSOCIATION OF MASSACHUSETTS.

OPHTHALMIC MOUNTING.

Application filed January 22, 1926. Serial No. 83,063.

This invention relates to ophthalmic mountings and has particular reference to an improved process for making the same.

The principal object of the invention, is to provide improved means for making a composition ophthalmic frame including rims and bridge from a single piece of stock.

Another object of the invention, is to provide improved means for making an ophthalmic frame from a composition material such as celluloid, combined with metallic parts wherein the composition part is of a single piece of material with portions thereof reinforced by metal.

Another object of the invention, is to provide means for making the rims and bridge members of an ophthalmic mounting from a single tubular member.

Another object of the invention, is to provide economical means for making a composition ophthalmic mounting.

Another object is to provide simple and efficient endpiece connections for an ophthalmic mounting of this description.

Other objects and advantages of my improved construction should be readily apparent by reference to the following specification taken in connection with the accompanying drawings, in which similar characters designate similar parts throughout, the preferred form of the invention only having been shown and described by way of illustration.

Referring to the drawings:

Figure 1 is a rear elevation of an ophthalmic mounting embodying the invention.

Figure 2 is a perspective view showing a composition tubular member used in the invention.

Figure 3 is a perspective view showing a step in the process of manufacture.

Figure 4 shows another step in the process of manufacture.

Figure 5 shows a further step in the process of manufacture.

Figure 6 shows a still further step in the process of manufacture.

Figure 7 shows a still further step in the process of manufacture.

Figure 8 is a detailed perspective view partly shown in section of the endpiece construction used in the invention.

Figure 9 is a fragmentary sectional view of a modification.

Figure 10 is a view showing a further modification.

Figure 11 is a view showing a still further modification.

Prior to this invention, ophthalmic frames were formed by either blanking the fronts from sheet composition such as celluloid or by forming them over metal rims. In the blanking process 75 per-cent of the sheet stock went to waste. This composition sheet stock is very costly, so it is readily seen that with this amount of waste and the operations through which the fronts have to be carried that the frames are an expensive article to manufacture, and great care has to be taken in finishing the frames to the size and shape desired. Another great difficulty in the prior art is that due to the facial characteristics of individuals varying in width of nose, pupillary distance, overhang of eyebrows, etc., it has been necessary to provide various sizes of frames and shapes of bridges to meet the dealers' demand. In order to meet this demand an individual blanking die has to be provided for each shape and size required, thereby causing the manufacturer to provide a great number of blanking dies that are very costly and which have to be replaced very often due to the effect of the composition on the cutting edge of the dies. This also adds greatly to the expense in making frames of this character with the result that they have been a very costly article to place on the market when finished.

In forming frames over metal, the composition has to be grooved, curled, notched and fitted at the bridge connection and positioned over the metal frames after which rivet pins or the like are used to hold the rims in place. This makes a long and expensive process of manufacture.

In this invention this loss of stock, cost of blanking dies, grooving, etc., is obviated and the process of manufacture is simplified so as

to produce a quickly made and inexpensive ophthalmic frame that will meet all the requirements described above.

Referring more particularly to the drawings, the numeral 10 is employed to denote the usual lens rims of an ophthalmic mounting having the split end pieces 11 for the temples 12.

Disposed centrally of the mounting and between the pair of lens rims 10 is the bridge member 13 adapted to hold the lens rims 10 a fixed distance apart and in accurate position on the face of the wearer.

Mounted within a suitable recess in the bridge member 13 is a reinforcing member 14.

Mounted on one end of the lens rims 10 by the rivet pins or the like 15 is a plate member 16 having mounted thereon a recessed lug 17. A second plate member 18 is mounted on the opposite ends of the lens rims 10 by the rivet pins or the like 19 and also has mounted thereon a recessed lug member 20.

Positioned on the outer end of the plate member 18 is a hinge member 21 adapted to receive a second hinge member 22 carried by the temples 12. These plate members having the recessed lugs, are adapted to be aligned and fitted together to form the end-piece members 11.

A screw 23 is inserted in the recessed lug 17 and is then threaded into the second lug 20 to clamp the lens rims or frames 10 around a lens.

A second screw 24 mounted in the hinge member 21 serves as a pivot pin for the hinge member 22 and also as a temple retaining dowel.

It will be apparent that with the endpiece construction described that temples may be interchanged without disturbing the lenses and on the other hand, the lenses may be removed without disturbing the temples.

In forming ophthalmic mountings of the character described I preferably make use of a piece of tubular stock 25 in which I saw or blank the slots 26 having the offset cuts 27. By so doing I form the arms 28 and 29 respectively, which I spread outwardly as illustrated in Figure 4. While the arms 28 and 29 are in their outward positions I bend the ends 30 and 31 as illustrated in Figure 5. I next insert the metallic reinforcing member 14 in the recess 32 of the center portion 33. This center portion 33 is then bent to form the bridge member 13 as shown in Figure 6. Following this operation I form the eyes or lens rims 10 by bending as illustrated in Figure 7, after which the plate members 16 and 18 are mounted in place to form the end pieces 11.

It will be apparent that by splitting a tubular member in this way the split recessed

portion will form a groove 34 in which the lens is held, thereby eliminating the necessity of a grooving operation as would be the case if a piece of composition bar stock were used instead of the tubular member.

I do not wish to limit my process to the use of tubular stock however as the same result may be obtained by the use of bar stock as stated above.

Referring to Figure 9 I show a modification in which I produce a composition frame having a reinforcing metal frame 35. This metal frame is formed by inserting a tubular metal core 36 within the tubular composition member 25 and sawing or slotting the same as heretofore stated for the composition tube. Following the slotting operation it is formed in the same manner as the tubular composition member 25.

In this case the split recessed portion 37 of the tubular metal core 35 forms the slot or groove to receive the lens and also forms a continuous reinforcing bridge member 38.

In Figure 10 I show a further modification in which the ends of the lens rims 10 are cemented together as at 39 and a separate temple receiving portion 40 having 90 mounted thereon the hinge member 41, is fitted and cemented to the outer periphery of the lens rims 10 as at 42. This forms a solid composition frame.

In Figure 11 I show a still further modification similar to Figure 9 in which I provide a split endpiece 43 having the members 44 and 45 respectively soldered to the ends 46 and 47 of the metal core 35. The temple 48 is mounted upon the dowel 49 within the recess 50 formed by the endpiece members 44 and 45. A screw 51 is used to clamp the members together. With this construction I form what is called an innerlined frame which is lighter in construction than the ordinary composition frame.

From the above it will be readily appreciated that there has been provided a structure which will accomplish all of the objects and perform all the functions set forth. It is also to be understood that various modifications may be found desirable in the construction and arrangement of parts, and the right is hereby reserved to make such changes as properly fall within the scope of the appended claims without departing from or exceeding the spirit of the invention.

Having described my invention I claim:

1. In a device of the character described, lens rims having offset abutting endpieces, a plate on one endpiece having a projecting lug, a plate on the other endpiece having a projecting lug and a hinge connection, said projecting lug being aligned with the lug on the first endpiece, means for securing the two lugs together, and a temple having a hinge

connection adapted to engage with the hinge connection on the plate on the second end piece.

2. In a device of the character described, 5 lens rims having offset abutting end pieces, one end piece fitting into a recess in the other end piece, a plate on the inset end piece having a projecting lug, a plate on the other

end piece having a projecting lug and a hinge connection, said projecting lug being aligned 10 with the lug on the first end piece, means for securing the two lugs together, and a temple having a hinge connection adapted to engage with the hinge connection on the second end piece.

GEORGE C. FAVRE.
